STRAND WINDING MACHINE

Evelyn Lyndall Whitby, Woodstock, Ontario, Canada, assignor, by mesne assignments, to Rain-Beau Products Company, a corporation of Massachusetts

Application September 2, 1949, Serial No. 113,711

17 Claims. (Cl. 242—18)

1

This invention relates to a strand winding machine.

The general object of the invention is the provision of a winding machine so constructed as to be automatic in the operation thereof, thereby providing for a continuous automatic operation when the machine is started.

Another object of the invention is the provision of a winding machine for transferring a filled bobbin to a location distant from the position of winding the yarn thereon.

Another object of the invention is the provision of a winding machine having two alternative drives which will operate automatically to disengage one drive and to engage the other drive.

Another object of the invention is the provision of a detector unit for a full bobbin which will be positive in its action.

With these and other objects in view, the invention consists of certain novel features of construction, as will be more fully described and particularly pointed out in the appended claims.

In the accompanying drawings:

Figure 1 is a plan view of a machine on a reduced scale embodying one form of the invention;

Figure 2 is a sectional view taken substantially along line 2—2 of Figure 1;

Figure 3 is an elevational view, partially in section, of a fragmental portion of the bobbin supporting centers and yarn traverse motion;

Figure 4 is a sectional view taken substantially axially through the driving center;

Figure 5 is a sectional view taken along line 5—5 of Figure 2;

Figure 6 is an elevational view of the mechanism for initially wrapping and securing the yarn on an empty core;

Figure 7 is a similar view but showing the parts in different relation to each other;

Figure 8 is a plan view of a detector and drive locking mechanism;

Figure 9 is a sectional view of a detail of the detector mechanism;

Figure 10 is a sectional view taken along line 10—10 of Figure 1 looking in the direction of the arrows;

Figure 11 is a perspective view of a portion of the traverse mechanism showing the yarn guide portion thereof;

Figure 12 is an elevational view partially in section showing the mechanism for removing a filled bobbin from between the support therefor;

Figure 13 is a similar view on a reduced scale

5 additionally showing the empty core supply and other associated parts;

Figure 14 is an elevational view partially in section showing the drive locking device and associated parts;

Figure 15 is a view of a detail of construction on an enlarged scale shown in Figure 14;

Figure 16 is an elevational view showing the cam for operating the lock and its relation to the lock operating lever;

Figure 17 is a sectional view taken along line 17—17 of Figure 6; and

Figure 18 is a sectional view taken substantially along line 18—18 of Figure 1.

Briefly, the invention comprises a machine so constructed as to provide for continuous automatic operation while the machine is in motion, for winding yarn about a core of a type which is to be used as a supply package for yarn to be fabricated into a fabric as distinguished from a yarn which is packaged for the purpose of transportation or storage to be later combined and re-wound in the final package form. Accordingly, means are provided for supporting and rotating a core to be filled. A detector mechanism or device is provided which operates upon the core being filled to set into motion mechanism to remove the filled core; position an empty core in place to have yarn wound thereon; sever the yarn from the filled core and again position the severed strands upon a fresh empty core, all this being accomplished automatically when the machine is in motion.

Referring to the drawings for a more detailed description of the invention, 20 designates generally a machine embodying one form of the invention which is so constructed as to be adapted for winding yarn or thread on braider carrier bobbins or the like 21. The bobbin shown is of a usual construction and has a cylindrical core or body 22 provided at each end with a head 23 and 24. The head 24 has radially extending ratchet-like teeth 25 which in the present instance are engaged by the bobbin driving means of the machine to rotate the bobbin. The bobbin 21 has a usual central opening 26 extending therethrough and is mounted for rotation between centers designated generally 27 and 28 (see Figure 2), each of which is mounted in a manner so that it may be retracted when doffing.

The center 27 is the driving center (see Figures 2 and 4) and comprises a spindle 29 which is provided adjacent one end thereof with oppositely disposed driving fingers 30. The fingers are

spaced from the end of the spindle a short distance providing a pilot 31 to be projected into engagement with the wall of the opening 26 in the bobbin to support the same at one end thereof. The driving fingers 30 engage with the teeth 25 of the bobbin to transmit rotation of the spindle to the bobbin. The spindle 29 is slidably received in a sleeve 32 which is of greater length than the bobbin 21 and has an enlarged head 33 which is provided with a diametrically extending recess 34. The fingers 30 are slidably received within the recess and provide a driving connection between the sleeve and spindle. The sleeve 32 is journaled in bearings 36 which extend upwardly from the base 37 of the machine and also has a longitudinal opening 35 extending therethrough. The other end of the sleeve 32 is closed by a threaded plug 38. A compression spring 39 is positioned between the inward end of the spindle 29 and the plug 38 and functions to yieldingly urge the spindle 29 to move it into engagement with the bobbin 21.

The center 28 (see Figure 2) comprises a thimble-like member 40 having a reduced body 41 providing a shoulder 42. The body 41 forms a pivot of a size to be slidably received in the opening 26 at the other end of the bobbin and with the shoulder 42 engaging against the head 24. The thimble freely rotates on a spindle 43, and is attached thereto by a split ring connection 44. The spindle 43 is slidably supported in spaced bearings 45 and 46 which extend upwardly from the base 37. A collar 47 which has a recess 48 is positioned on the spindle 43 adjacent to and in telescoping relation with the thimble. A collar 49 which has a recess 50 in the outer wall thereof is adjustably secured to the spindle 43 at a location thereon between the bearings 45 and 46. A compression spring 51 encircles the rod with one end thereof abutting against the bearing 46 and the other end thereof against the collar 49 so as to yieldingly urge the thimble to be moved into engagement with the bobbin 21 in the manner previously described. The bearing 45 is extended as at 53 by means of a sleeve 54 which is secured in place by a screw 55.

The rotation of the sleeve 32 and the spindle 29 connected thereto is accomplished in the instant application by means of a friction wheel 56 (see Figure 1) which is carried by the sleeve 32 and which is engaged by a friction drive wheel 57. The periphery of the wheel 57 may have a covering 58 of any suitable material such as leather so as to insure proper frictional contact with wheel 56. The friction drive wheel 57 is carried on a shaft 59, one end of which is journaled in a bearing support 60 which extends upwardly from the base 37. The other end of the shaft 59 is journaled in a bearing 61 (see Figures 13 and 14) which is supported on an integral arm 62 pivotally attached as at 63 to a bracket stand 64 which rises from the base 37. The arm 62 is moved counter-clockwise, as viewed in Figure 14, by means of a pull spring 65 which is attached at one end to the arm 62 and its other end to a laterally extending support 66 fixed to the stand 64 such as by means of a screw connection 67. Thus, the shaft 59 is mounted in a manner so that the same may be swung with the bearing 60 as a fulcrum so as to move the friction drive wheel 57 into and out of engagement with the pulley 56. The bearing 60 is not shown in detail and may be of any suitable manufacture wherein a slight pivotal movement of the shaft 59 may be

had for the purpose above described. The shaft 59 will hereinafter be referred to as the main drive shaft of the machine. A locking device designated generally 68 to be hereinafter described is provided for locking the friction drive wheel 57 and friction wheel 56 into engagement with each other.

In the present instance, motion is transmitted by means of a belt connection to the main drive shaft 59 from a power shaft 69 (Fig. 1) which is secured to the under side of the base 37. The power shaft 69 may be in turn driven from any suitable source of power (not shown) which may consist of an electric motor. The power shaft 69 carries a pulley 70 over which is trained a belt 71 which extends over a pulley 72 carried by a jack shaft 73 journaled in bearings (not shown) and positioned beneath the base 37. The jack shaft 73 also carries a pulley 74. The main drive shaft carries a pulley 75 and a belt 76 extends over the pulleys 75 and 74.

The yarn or thread to be wound on the bobbin 21 may be a single strand or may consist of a plurality of strands, each of which may be supplied from individual packages (not shown). When a plurality of strands are to be wound on a bobbin, the usual previous doubling operation, heretofore necessary so as to provide ply yarn prior to the winding thereof on braider carrier bobbins, is eliminated. In the instant disclosure the yarn Y is shown as a single strand but this is only for purposes of illustration. The yarn is led from a suitable supply source (not shown) through guides 77 and 78 and to the bobbin 21. The traverse of the yarn back and forth across the bobbin is accomplished by means of a traverse motion mechanism designated generally 79 (see Figures 1, 2, 3, 8, and 13). The mechanism comprises a bar 80 having a recess 81 substantially midway at the upper edge thereof (see Figure 11). A pair of flat thin blocks 82 are positioned across the recess end to end lengthwise of the bar 80 but spaced from each other a distance so as to provide a narrow space or guide slot 83 at a location substantially midway of the recess 81. These blocks are secured in place such as by means of screws 84. The bar 80 is secured to a traverse rod 85 by means of end members or brackets 86, each of which has a similar recess 83 at the upper end thereof (see Figure 8) in which is snugly received the ends of the bar 80. The bar 80 is fastened in place to these brackets by means of pin or the like connection 89. The lower end of each bracket is provided with an opening 90 through which passes the traverse rod 85. The brackets are adjustably secured to this traverse rod by means of screws 91.

The traverse rod 85 is slidably supported at one end thereof in a bearing 92 (see Figure 1). The other end of the traverse rod is made rectangular in cross section and is slidably mounted in spaced guides 93. The traverse rod 85 is reciprocated by means of a circular cam 94 having a cam groove 95 in the periphery thereof. The cam is suitably mounted on a shaft 96 which is journaled in bearings 97 and is operatively connected to the traverse rod 85 by means of a cam follower 98 which is secured to the traverse rod 85 and additionally supported by means of a rod 99 extending through the follower and secured thereto. The rod extends parallel to the traverse rod and is slidably mounted in guide openings 100. The follower has a pin 101 which extends into engagement within the groove 95. Rotation of the cam is accomplished by means

of a worm gear wheel 102 carried on the shaft 96 and engages with a worm 103 that is carried by a vertical shaft 104. The shaft 104 is journaled in a bearing 105 and projects through the base 37 and carries at the lower end portion thereof a beveled gear 106 which engages with a similar bevel gear 107 carried by the power shaft 69. The yarn Y is led from the guide 78 to lie in the recess 81 and in the guide slot 83 between the blocks 82. With the cam in motion the traverse rod 85 and the bar 80 attached thereto will be reciprocated, and the yarn will be traversed back and forth across the bobbin 21 in a well-known manner.

When the bobbin 21 becomes filled, a detector mechanism designated generally 108 operates to set in motion mechanism to trip the locking device 68 (see Figure 15) whereby to disconnect the bobbin drive. The detector mechanism comprises an annulus or trip wheel 109 (see Figures 1, 8, 9, and 13) having a wedge-shaped section 110 which extends to substantially the center of the wheel and has a mounting opening 111 therein positioned eccentrically relative to the center 112 of the wheel. The trip wheel 109 is mounted for free rotation of an arm 113 which has a bifurcated end providing spaced arms 114 between which the trip wheel is positioned and secured by means of a pivot pin 115. The arm 113 also has side extensions 116 and is carried by a shaft 117 having a threaded reduced end portion 118 which extends through the other end of the arm and is engaged by a nut 119 so as to fasten the arm and the shaft to each other. The shaft 117 is in turn journaled in bearings 120 which are carried by a bracket 121 that is secured to the upper edge of the stand 64 such as by cap screws 122. The arm 113 extends from the shaft forwardly to a point directly over the body of the bobbin and positions the trip wheel 109 at a location to be engaged by the yarn of a filled bobbin. The periphery of the wheel 109 is spaced from the axis of the bobbin a predetermined distance which may be varied according to the nature of the work by means of an adjusting threaded member 123 which threadedly extends through the extension 116 and into engagement with shelf 124 carried by the bracket 121. A lock nut 125 secures the member 123 in adjusted position.

It will be noted with reference to Figure 9 that the trip wheel is in effect a cam having a high side 126 and a low side 127 weighted by the sector to normally position the low side of the trip wheel adjacent the bobbin. When the yarn placed upon the bobbin builds up sufficiently, the trip wheel 109 will be engaged and rotated. Because of its eccentric mounting a partial rotation thereof will swing the arm 113 upwardly sufficiently to rock the shaft 117. This motion is transmitted to a short arm 128 which carries at one end thereof a pin 129 that projects laterally thereof and is fixed at the other end to the shaft 117. The locking device which is tripped through the action of the pin 129 consists of a catch part 130 and a latch part 131 (see Fig. 15). The catch consists of a member 132 which is suitably secured to the upper side of the bearing 61 centrally thereof and extends substantially vertically therefrom. The upper portion of the member 132 is slotted lengthwise forming a shoulder 133 and providing spaced arms 134.

The latch 131 (see Figs. 8, 14, 16) is made in two sections 135 and 136, with the adjacent end

portions 137, 138 thereof placed side by side in overlapping relation. Each end of the overlapping portions of the sections is provided with a similar slot 139 and 140 which extends lengthwise of the sections. The section 135 has a pin 141 fixed thereto which extends through the opening 140 (see Figure 14), while the section 136 has a similar pin 142 fastened thereto which projects through the opening 139 in the other section. Both of these pins project substantially an equal distance on the side of the section 136 and a pull spring 143 has its end anchored to the pins 141, 142 whereby the sections 135, 136 are yieldingly urged toward each other. The sections 135, 136 are movably held together by a stud connection 144. The free end of the section 135 extends between the arms 134 and has a notch 145 in the lower edge thereof providing an abutment 146 which may be moved into engagement with the shoulder 133. The section 135 is also provided with a guide 146 which has an arm 147 spaced from the lower edge of the section 131 providing an open recess 148. The guide is attached to the section by means of cap screws 149. The free end of section 136 is pivotally mounted on the upper end of a vertically extending lever 150 (see Figure 16) by means of a pivot pin 151. The lower end of the lever 150 is pivotally supported by a bracket 152 by means of a pivot pin 153.

The pin 129 on the arm 128 projects through the recess 148 and when the arm 128 is rocked by the parts associated therewith, the pin 129 will lift the latch 131 and disengage the abutment 146 from the shoulder 133, whereupon the arm 132 under the influence of the pull spring 65 will be moved counter-clockwise as viewed in Figure 14 to move the friction drive wheel 57 out of engagement with the friction wheel 56 and the bobbin drive will come to rest.

Provisions are also made whereby the latch may be manually disengaged from locking position. To this end, a cam 154 is provided (see Figures 8, 10 and 14). The cam 154 in the present instance is in the form of a disc having a handle 155 and opening 156 which is eccentrically disposed relative to the center of the disc. The cam is rotatably mounted on the portion 137 by means of the stud 144 which has a head 157 and a reduced threaded end 158 which extends through the portion 138 and is fastened thereto by a nut 159. The stud extends through the opening 156 in the cam and through an elongated opening 160 in the section 135 thus providing for relative sliding relation between the sections. The section 135 has a pin 161 which extends into engagement with the periphery of the cam 154. Turning the cam on the stud counterclockwise, as viewed in Figure 14, and applying a slight lifting force, will through the pin 161 move section 135 to the left against the urge of the spring 143 and disengage the abutment 146 from engagement with the shoulder 133. Upon the release of the locking device 68 either automatically through the action of the trip wheel 109 or manually by means of the cam 154, mechanism, which is cam actuated and operable for providing the several motions required for automatic doffing, will be set into motion. These control cams, of which there are nine in number in the present disclosure are designated 162, 163, 164, 165, 166, 167, 168, 169, and 170 respectively and in the order in which each performs its function (see Figure 1). These cams are mounted on a cam shaft 171 which is journaled in spaced bear-

ings 172 and 173 extending from a common support 174 fixed to the base 37. The cam shaft 171 is rotated by means of a worm wheel 175 which is carried at one end of the cam shaft and is engaged by a worm 176 mounted on a vertical shaft 177, a portion of which projects below the base 37. The lower end of the shaft 177 carries a pulley 178 through which motion is transmitted to the shaft.

Motion is transmitted to the pulley 178 from a drive source which may be considered and hereinafter referred to as the secondary drive designated generally 179 (see Figure 1). The secondary drive consists of a driven wheel 180 which carries a grooved pulley 181 which may be formed integral with the wheel. The driven wheel 180 is carried by a shaft 182 and is fixed thereto in any appropriate manner so as to rotate therewith. The shaft is journaled in a bearing support 183. The wheel 180 is positioned at a location to be engaged by a friction wheel 184 which is secured to the main drive shaft 59. When the main drive shaft 59 is moved to disengage the wheel 57 with the wheel 56, the friction wheel 184 will be moved into engagement with the driven wheel 180 so as to rotate the same; that is, the movement of the drive shaft in one direction will disengage the bobbin drive and place the secondary drive in action. The movement of the drive shaft in the opposite direction will disengage the secondary drive and place the bobbin drive in action. A belt 185 is trained over the pulley 181 and extends through a suitable opening (not shown) in the base 37 at a location beneath the pulley 181. The belt 185 extends over guide idler pulleys 186 and on over the pulley 178 whereby upon rotation of the shaft 182, motion will be transmitted to the cam shaft.

In order to re-engage the bobbin drive, the lever 150 (see Figure 16) is provided with a cam follower 187 which engages with the surface of the cam 170. The cam 170 in the instant disclosure is circular and has a depression or recess 188 therein in which the follower will ride when opposite thereto. The follower is maintained in engagement with the cam surface by means of a pull spring 189 which is attached at one end to the lever and at the other to a pin 190 which may be secured to the base 37. Upon the follower 187 entering the recess 188, the latch 131 will be moved forward by the movement of the lever 150 a distance sufficient to position the abutment 146 beyond the shoulder 133 and in position to engage the same upon the latch dropping by gravity. Upon further rotation of the cam 170, the follower will ride out of the recess 188 and onto the periphery of the cam and swing the lever 150 in the opposite direction to engage the abutment with the shoulder 133 and pull the member 132 to swing the arm 62 about its pivot 63 and move the friction drive wheel 57 into driving relation with the pulley 56.

The removal of a filled bobbin 21 from between the centers 27 and 28, and its discharge such as through an opening 191 in the base of the machine to be received in a suitable receptacle (not shown) is accomplished by means of a carrier designated generally C (see Figures 1, 12 and 13). The carrier comprises spaced members 192, each of which is similarly constructed of resilient material bent into U shape providing resilient fingers 193, between which there is positioned a support 194 secured in place by screws 195. Each member 192 is fastened in spaced relation on a shaft 196 which is rotatably sup-

ported on a movable frame designated generally 197 comprising a pair of generally parallel and vertically extending arms 198 and 199. Each arm is of a general U formation providing lateral extensions 200 and 201 at the upper end thereof. The upper ends of the arms are secured to each other in spaced relation by means of a tie rod 202 extending through the extension 201 and secured in place by nuts 203. The lower end of the arms are secured to each other in a similar manner by means of a tie rod 204 and nut connection 105. The shaft 196 is journaled in the extension 200 with the resilient fingers 193 extending towards the bobbin 21.

15 The frame 197 is pivotally attached intermediate the ends thereof to a bracket support 205 having spaced ears 206 which is secured to the under side of the base in any convenient manner such as by cap screws 207. The arms of 20 the frame 197 extend between the ears and a pivot pin 208 having threaded ends passes through the ears and arms and is secured in place by nuts 209 engaging the threaded end thereof. The frame is moved or swung about 25 the pivot pin 208 by means of a lever 210 which extends generally vertically and is pivotally mounted on a support (not shown) by a pivot pin 211. The lower end of the lever 210 is pivotally connected to the frame 197 by a link 212 30 pivoted as at 213 and 214. The lever 210 extends through a suitable opening 215 in the base 37 to adjacent the cam 162 (see Figure 1) and carries at the upper end a cam follower 216 which may be in the form of a pin which projects into engagement with the cam 162. A pull 35 spring 217 has one end anchored to the under side of the base 37 as at 218, and the other end thereof is fastened to the lower end of the lever 210 as at 219. The spring 217 will move the 40 lever 210 so that the pin 216 will follow the periphery of the cam 166 so as to cause the frame to be swung counter-clockwise as viewed in Figures 12 and 13 and move the fingers 193 into engagement with the heads of the bobbins.

45 These fingers 193, as previously described, are resilient and are spaced a distance less than the diameter of the bobbin heads and will be spread apart upon riding over the bobbin heads whereby a tension will be placed on the fingers sufficient to firmly hold the bobbin therebetween 50 during the transfer thereof to the point of discharge. In operation the frame is swung from the full line position shown in Figure 12 to the forward position to engage the heads of the bobbins as shown in dot and dash line 220. The fingers will remain in the dot and dash line position until the centers are retracted or withdrawn from engagement with the bobbin. The fingers 193 are guided in their movement toward 55 and away from the centers by means of a lever 221 (see Figure 12) which is fastened at one end thereof to an end of the shaft 196 and carries at the other end thereof a pin 222. The pin 222 engages with a cam surface 223 which is provided on a support 224. The pin 222 is biased 60 into engagement with the cam 223 by means of a grooved pulley 225 which is attached to the other end of the shaft 196. A pull spring 226 is secured at one end thereof in the groove of the pulley 225 and at the other end to the base 37 as at 227.

65 Upon withdrawal of the centers 27, 28 from engagement with the bobbin in a manner to be hereinafter described, the frame 197 will be 70 moved in the opposite direction by the action 75

of the cam 162. The pin 222 riding on the cam surface 223 will turn the shaft 196 counterclockwise about its axis, as viewed in Figure 12, and swing the fingers 193 with the bobbin carried thereby downwardly to opposite the opening 191 in the base 37. During the rearward movement of the frame 197 to the position shown in dot and dash line 228 in Figure 12, the bobbin will engage stripper fingers 229 which are secured to the base 37 as at 230 (see Figures 1 and 12) and rise at an angle to the path of movement of the bobbin to be engaged thereby to be stripped from between the fingers 193 of the carrier. Upon further movement of the cam after the bobbin has been stripped from the fingers the frame will be again moved under urge of the spring 217 forwardly to the initial position, as shown in full lines in Figure 12.

The centers are withdrawn from engagement with the bobbin substantially simultaneously through the action of the cams 164, 165. The center 27 is withdrawn by means of a collar 231 (see Figures 1 and 4) which is positioned about the sleeve 32 and over the opening 35 therein. A set screw 232 threadedly extends through the collar 231 and into frictional engagement with the spindle 29. A lever 233 (see Figures 1 and 3) has the lower end thereof secured to a shaft 234 and extends upwardly into engagement with the collar 231. The shaft 234 is journaled at one end thereof to a bracket 235. The other end of the shaft 234 is journaled in the support 174 and carries a lever 236 which extends upwardly therefrom and has a cam follower 237 secured thereto which projects into engagement with the cam 165 to be moved thereby and in turn rock the lever 233 to slide the spindle 29 within the sleeve 32 and out of engagement with the head 23 of the bobbin, the center being returned into engagement with an empty bobbin by means of the spring 39 as previously described.

The center 28 is similarly withdrawn from engagement with the bobbin by means of a lever 238 having a pin 239 at the upper end thereof projecting into the recess 50 in the collar 49 (see Figures 1 and 2). The lever 238 is carried by a shaft 240, one end of which is journaled in a support 241 and the other end thereof in a support 242. A second lever 243 is carried by the shaft 240 and extends upwardly and has a cam follower 244 secured thereto which projects into engagement with the cam 164 to be rocked thereby to move the collar 49 to the left, as viewed in Figures 1 and 2, to withdraw the thimble 28 from engagement with the bobbin. The thimble 28 is moved into engagement with an empty bobbin by means of the compression spring 51, as previously described.

Prior to the removing of a filled bobbin from between the centers, the yarn strand Y is disengaged from the traverse 79 which is in continuous motion when the machine is in action. This is accomplished by means of a U-shaped member 245 (see Figure 8) having a body 246 with arms 247 extending therefrom. The body is of a length to extend the full distance of the traverse motion and is positioned between the traverse bar 80 and the guide 78. The arms 247 extend at right angles to the body and into engagement with a shaft 248. The arms may be fastened to the shaft in any suitable manner such as welding thereto as at 249 as to rock therewith. The shaft 248 is rockably mounted in a support 250 which for convenience is positioned beneath the bobbin 21. The end of the shaft 248 carries

a lever 251 having an arm 252 which depends therefrom. The shaft 248 is rocked about its axis by means of a lever 253 (see Figure 10) which is pivotally mounted on the bracket 122 by means of a pivot pin 254. The lower end of the lever 253 is L-shaped providing an arm 255, the end of which is movably secured to the arm 252 such as by means of a pivot connection 256. The upper arm 257 of lever 253 is secured to the arm 132 to be rocked thereby. To this end, a support 258 is attached to the upper end of the arm 132 such as by means of a nut and bolt connection 259 (see Figure 8). The support 258 extends substantially horizontal and has an opening 260 (Figure 8) at the free end thereof through which a rod 261 slidably projects with the inward end portion thereof secured to the upper portion of the lever such as by means of a hook 262 formed at the end of the rod and which engages in a proper opening 263 in the arm 257. The other end of the rod 261 is threaded and receives nuts 264. A cushioning compression spring 265 encircles the rod 261 between the support 258 and the nuts 263. The movement of the arm 132 upon the release thereof by the tripping of the latch 131 will move the rod 261 in a direction to swing the lever 253 clockwise, as seen in Figure 10, to rock the shaft 248 clockwise and move the body 246 upwardly a distance sufficient to engage and move the yarn Y from engagement with the traverse.

In the cycle of operation of the carrier, the fingers 193 are moved forward to engage a filled bobbin and then come to rest so as to permit the centers to be withdrawn, and then are moved rearwardly a distance sufficient to clear an empty bobbin to be positioned between the centers and then momentarily come to rest. Empty bobbins to be in turn placed between the centers 27 and 28 to be filled with yarn are carried in a hopper designated generally 267 (Fig. 13) having rear, side, and front walls 268, 269, and 270 respectively providing thereby a compartment 271 open at the top and bottom. The compartment 271 is of a size in cross section to slidably receive the empty bobbins 21. The hopper is also open in the front as at 272 whereby the bobbins may be viewed or manually manipulated when desired. A stop 273 upon which the lowermost empty bobbin rests is secured to the rear wall 268. The hopper is mounted to be in a normally generally vertical position at the rear of the centers in such a manner that the lower end thereof may be swung to position the lowermost empty bobbin between the centers. This is accomplished by pivotally mounting the upper end of the hopper by means of perforated spaced ears 274 (see Figure 1) which extend rearwardly from the upper portion of the rear wall 268. A rod 275 extends through the ears with the end portions thereof fixed in vertical supports 276 and 277 which are secured to the base 37 on either side of the hopper.

In order to hold the lowermost empty bobbin in proper position to be transferred to the centers, a pair of fingers 278 are secured in spaced relation on a rod 279 in a manner so as to depend therefrom into engagement with the lowermost empty bobbin (see Figures 3 and 13). The rod 279 is rockably mounted in ears 280 which extend forwardly from the side of the hopper. The fingers are yieldably held in contact with the lowermost bobbin by means of a lever 281 which is attached to one end of the rod 279. A pull spring 282 (Fig. 3) has one end attached to the lever 281 and the other end attached to a suitable support

which may be a pin 283 attached to the side wall 269 of the hopper.

The hopper is normally held in the vertical position and swung forwardly to position an empty bobbin between the centers upon the withdrawal of the filled bobbin by means of an arm 284 which is fastened to the rear wall 268 and carries at the free end thereof a roller 285 (see Figures 1 and 13). A lever 286, the lower end of which is pivotally secured to a support 287, extends upwardly into engagement with the roller. A cam follower 288 is attached to the lever 286 and projects into engagement with the cam 166. Upon movement of the cam 166 the lever will be swung about its pivot and in turn swing the hopper to the position shown in Figure 13, so as to position the lowermost empty bobbin 21a in line with the centers. In proper sequence, the centers 27, 28 will be released from the retracted position and through the actions of the springs 39 and 51, previously mentioned, the centers will be moved into engagement with the empty bobbin, whereupon the hopper will be moved to initial position through the action of a pull spring 289 which may be attached to the rear wall 268 of the hopper at any convenient location thereon and with the other end thereof to a support 290 (Fig. 13) which may extend from any convenient location on the machine.

Upon an empty bobbin having been positioned and engaged by the centers 27 and 28, a mechanism designated generally 291 is set in motion to wrap the yarn about the empty bobbin now in position between the centers. This mechanism (see Figures 2, 3, 6, and 7) comprises a grooved pulley 292 having a hub 293 on one side thereof which is provided with an annular groove 294. On the opposite side of the pulley there is provided diametrically disposed arms 295 which extend axially from the pulley. Each arm is slotted as at 296 and receives therein a driving finger 297 which is pivotally secured to the arm such as by means of a pivot pin 298. The fingers 297 are rounded at the free end thereof and carry a pin 299. A pull spring 300 is attached to pins 299 whereby the fingers 297 are tensioned toward each other against a stop pin 301 carried by each arm 295.

The pulley 292 (Fig. 17) is slidably mounted on the bearing 53 to be moved in a manner to be hereinafter described so as to position the fingers 297 into engagement with the adjacent end of the bobbin, whereupon rotation of the pulley the bobbin will be rotated thereby. The yarn Y to be wrapped about the empty bobbin is held in a holder designated generally 302 which is carried by the pulley 292 so as to be revolved thereby about the axis of the empty bobbin. The holder comprises a rod 303 (Figs. 6, 7) having an enlargement or a head 304 at one end thereof and slidably receives thereon a cup-like member 305. A compression spring 306 of a relatively fine wire encircles the rod 303 between the head 304 and the cup 305. A second spring 307 of a heavier wire encircles the rod 303 on the other side of the cup 305. The end portion of the rod between the cup and the head is recessed as at 308 for a purpose to be hereinafter described. The rod 303 slidably extends through the bight of a U-shaped member 309 which provides an abutment 310 for the spring 307 to act against. The arms 311 of the member 309 are positioned to straddle an enlargement or block 312 extending from the flange of the pulley 292 and are there secured in position such as by means of screws 313. The end

of the rod 303 also slidably extends through the block and flange of the pulley (see Figure 2). The rod 303 is secured in place by means of a collar 314 which is positioned on the rod at a location to be between the arms 311 and there secured to the rod such as by a screw 315. The collar 314 is provided with a fork arm 316 which extends upwardly to straddle the spindle 43 so as to prevent the rod 303 from rotating about its axis.

It will be noted with reference to Figure 7 that when the pulley 292 is moved along the bearing 53 toward and into engagement with the bobbin, the spring 307 will be compressed which in turn will compress the spring 306 between the cup 305 and the head 304. It will be also noted from Figure 6 that when the pulley 292 is in the inactive position that the coils of the spring 306 are open which provides a space therebetween for the length of yarn Y which extends from the guide 78 to the filled bobbin 21 to engage therein. It is here also pointed out that the recess 308 is provided to assure sufficient depth between the coils for the yarn to be received therein.

Prior to the release of the filled bobbin from between the fingers 193, the yarn Y is severed. This is accomplished by means of a knife blade 316 (see Figures 1 and 3) carried at the end of a lever 317 which is pivoted to a bracket 318 by means of a pivot screw 319. The lever 317 is swung about its mounting to move the blade 316 across the yarn Y which extends from the guide 78 to the filled bobbin now in the position substantially as that shown in dot and dash line 320 in Figure 12. Means for moving the lever 317 includes a shaft 321 (see Figure 1) which is mounted at one end on the support 241 and at the other end on the support 242. A lever 322 has an arm 323 which extends upwardly and is provided at the upper end with a cam follower 324 which is projected into engagement with the cam 169. The other end of the shaft carries a lever 325, the arm 326 of which is connected to the lever 317 by means of a connecting link 327. The cam follower 324 is biased into engagement with the surface of the cam by means of a torsion spring 328 which encircles the shaft 321 and is secured at one end to a collar 329 in an appropriate manner and at the other end to some portion of the support 242 such as at 330.

The pulley 292 is moved along the shaft to position the fingers 297 carried thereby into engagement with the head of the empty bobbin, as previously described, by means of two similar levers 331 (Fig. 6) which are provided at their upper ends with pins 332 to engage into the recess 294 of the pulley 292 (see Figures 1 and 5). The lower ends of these levers are secured to a shaft 333 which is journaled at one end in the support 241 (Fig. 1) and at the other end portion in the support 242. A second lever 334 is carried by the shaft 333 and rises therefrom with the upper end portion carrying a cam follower 335 projecting into engagement with the cam 167. The cam follower 335 is maintained in contact with the cam 167 by means of a lever 336 attached to the shaft 333. A pull spring 331 is attached at one end thereof to the lever 336 and the other end thereof is attached to any convenient position to the base 37 as at 338. The pulley 292 when in the inactive position as shown in Figures 1 and 6 is prevented from free rotation by means of a lever 339 (see Figure 2) which is pivoted at the lower end by means of pivot pin 340 to a support

341. The upper end of this lever extends into engagement with a shoulder 342 formed by a recess in the end of the hub 293 (see Figure 5). The lever 339 is biased into engagement with the shoulder 342 by means of a pull spring 343 which is anchored at one end thereof to a support 344 and at the other end thereof to the lever 339. Upon sliding of the pulley towards the bobbin the same will ride out of engagement with the upper end of the lever 339. The lever will be prevented from following the pulley by means of a stop 345 which is positioned to engage the edge of the lever (see Figure 2).

Motion is transmitted to the pulley 292 from the secondary drive shaft 182 (Fig. 1) which is provided at one end thereof with a reducing gear cluster designated generally 346 which is engaged by a gear 347 carried by a shaft 348 that is journaled in spaced bearings 349 and 350. The shaft 348 carries a clutch-driven pulley 351 which has an elongated hub 352 (see Figure 18) and a friction surface 353. A belt 354 connects this pulley 351 with the pulley 292. A sleeve 355 having a reduced portion 356 providing a shoulder 357 is attached to the shaft 348 by means of a headless set screw or the like 358. The pulley 351 is rotatably mounted on the reduced portion 356 and a friction disc 359 of leather or like material is interposed between the shoulder 357 and the friction surface 353 on the pulley. The reduced portion 356 extends beyond the hub 352 and finds bearings in a fork lever 360, the sides of which engage the hub 352. The lower end of the lever 360 is secured to a shaft 361 which is journaled at one end in a bearing support 362 and at the other end of the support 342. A short lever 363 is secured to the shaft 361 and a pull spring 364 has one end thereof attached to the lever 363 and its other end to a similar lever 365 carried by the shaft 333 whereby when the shaft 333 is rocked by the cam 167, tension will be placed upon the lever 360 to move the pulley 351 into frictional driving relation with the sleeve 355 to be rotated thereby. It will be noted that when the pulley 292 is in the inactive position the pulley 351 will come out of driving relation with sleeve 355.

In order to prevent the yarn Y from dropping beneath the holder 302 upon the severing of the yarn, a guide finger 366 is provided (see Figures 1, 3 and 17). This guide finger 366 is movably mounted by means of a crank lever 367 to be moved just above the holder 302 so as to engage the yarn length extending between the guide 78 and the filled bobbin as being moved to the point of discharge. The lever 367 is pivotally mounted as at 368 to a support 369 and has an arm 370 which extends substantially horizontal from the pivot and has secured thereto the guide finger 366. The other arm 371 is connected by means of a link 372 to a lever 373 which is pivotally secured to a support 374. The lever 373 carries a cam follower 375 which is engaged by the cam 163 to be rocked thereby. Upon the lever being rocked by the cam 163 the lever 367 will also be rocked counter-clockwise as viewed in Figure 17 and raise the guide finger 366 from the full line position shown to that of the dot and dash line position shown.

After the yarn Y has been severed the guide finger 366 will be permitted to move out of line with the holder 302 and permit the severed yarn end to drop between the coils of the spring 306 whereupon the sliding movement of the pulley 292 will compress the springs 307 and 308 and 75 the withdrawal of the centers from the bobbin,

thereby firmly secure the yarn end to the holder. Upon the release of the pulley 292 from engagement with the lever 339, the pulley 292 will be free to be rotated and revolve the holder and the bobbin, carrying the yarn Y therewith. Substantially simultaneously with the start of rotation of the empty bobbin by the fingers 297, the guide 78 will be moved to traverse this initial length of the yarn on the bobbin to firmly tie the same into position. This guide 78 comprises a lever 376 (see Figures 1, 2, and 7) which is pivoted intermediate its ends as at 377 and carries at the upper end thereof a cam follower 378 which engages with the cam 168 to swing the lever about its pivot. The lower end of the lever carries an extension 379 which carries the yarn guide bushing 380 through which the yarn extends.

The action of the cam 168 on the lever 376 is such that the guide 78 will be swung to the position as shown in the full line position in Figure 7, then the lever 376 under the influence of the torsion spring 381 will follow the surface of the cam, and the guide will be returned to initial position and there remain stationary as shown in dot and dash line in this Figure 7, having in its movement crisscrossed the yarn about the core of the bobbin. While the yarn is held sufficiently firm between the coils of the spring the same will be pulled from therebetween upon the wrapping thereof about the package. In the present timing of the machine, the pulley 292 will revolve and carry the holder 302 for six revolutions about the core of the bobbin and then the pulley will again be returned to its initial position and into engagement with the lever 339 to prevent further rotation thereof.

Upon the disengagement of the fingers 297 from driving engagement with the bobbin, the cam 170 will have rotated sufficiently so as to permit the latch 131 actuated thereby to engage with the arm 132 to disengage the secondary drive and place the bobbin drive into action in the manner previously described.

The operation of the several parts of the apparatus has been given in connection with the detailed description thereof and, therefore, but a brief general description of the operation of the machine will be necessary for a complete understanding of the manner in which the machine operates. With an empty bobbin in proper position between the centers and the yarn engaged by the traverse motion, assuming the motor to be in action, the yarn will be wound about the body of the bobbin. When the bobbin has been sufficiently built up with yarn, the trip wheel 109 will be engaged to trip the latch 131 from engagement with the catch 130 whereupon the friction drive wheel 57 will be moved out of engagement with the pulley 56 and into engagement with the driven wheel 180 of the secondary drive 179. The filled bobbin will now come to rest and the cam shaft 171 will be set into motion through its connection with the secondary drive. The movement of the arm 62 to disengage the friction drive wheel 57 will also actuate member 245 to disengage the yarn from the traverse motion, which, as previously stated, is a continuous motion, while the machine is in action. The carrier 192 will now be set into action by cam 162 to move the fingers 193 into engagement with the heads of the filled bobbin and there momentarily come to rest. The centers are next withdrawn from engagement with the bobbin by the simultaneous operation of cams 164, 165. Upon the withdrawal of the centers from the bobbin,

the carrier 192 with the filled bobbin held therein will be moved rearwardly to a position just sufficient so as to clear the positioning of an empty bobbin between the centers. The guide finger 366 will now be raised or moved into position so as to prevent the yarn strands from accidentally being positioned beneath the holder 302 upon further movement of the filled bobbin to the point of discharge thereof. The hopper 261 will be swung by means of cam 166 to position the hopper to align an empty bobbin between the centers. With the empty bobbin in proper position, the centers under urge of springs 39 and 51 will be moved into engagement with the empty bobbin. After the centers have moved into engagement with the bobbin, the hopper will swing back to its initial position through the action of the pull spring 289. The carrier 192 is now set into motion for further rearward movement so as to carry the filled bobbin to a position above the opening 191 and to strip the bobbin from the carrier by means of the stripping fingers 229.

Prior to the release of the bobbins from the carrier, the blade 316 will be swung across the strands to sever the same through the action of cam 169 and associated parts. After severing the yarn, the guide finger 366 will be permitted to be moved out of line with the holder 302 and the severed yarn will drop between the coils of the spring 306. The driving fingers 297 will now be advanced into engagement with the head of the bobbin to rotate the same about its axis, the yarn wrapped about the bobbin core by holder 302. The yarn will now be laid about the bobbin and initial traverse by means of the actuation of the guide 78 through the action of the cam 168 and associated parts. After six revolutions of the holder about the bobbin the fingers 297 and pulley 292 will be moved to inactive position into engagement with the lever 339. Referring to Figure 2 it will be noted that the guide 78 is at a position to the right of the free end of holder 302 thereby locating said holder out of the path of the yarn initially wrapped about the bobbin.

After the drive fingers 297 have become disengaged from driving engagement with the bobbin, the cam 170 will have nearly completed one revolution to place the recess 188 at a position for the follower 187 to ride into. This will move the latch 131 forwardly of the catch 130 to permit the same to drop by gravity past the shoulder 133. The trip wheel 109 now being free to move will also drop to initial gauging position and rock the shaft 117 in the direction to move member 245 from the blocking position through the linkage connection with shaft 117 whereupon the yarn Y will be permitted to ride into the traverse slots 81, 83. Upon further movement of the cam, the follower 187 will ride out of the recess onto the periphery of the cam and move the latch to disengage the secondary drive to bring the cam shaft to rest and re-engage the bobbin drive. It is here pointed out that the doffing of the bobbins is accomplished during one complete rotation of the cam shaft.

In order to move the trip wheel out of the path of movement of the hopper as the same is swung forwardly, an abutment or roller 281 is secured to a strap 282 which is fixed to the side of the hopper (see Figures 13 and 14). This roller projects into engagement beneath the latch 131 and will raise the latch as the hopper is moved forward. The pin 129 which extends in the space 148 will be moved to swing or rock the shaft 117 in a direction so as to raise the trip wheel 109

out of the path of movement of the hopper as best seen in Figure 13.

I claim:

1. A strand winding machine comprising means for rotatably supporting a core about which yarn is to be wound, a drive means for engaging one end of said core for rotating the same, a second drive means for engaging the other end of said core for rotating the same and means for engaging either one of said drives for rotating said core, each of said drives rotating said core in the same direction.

2. A strand winding machine comprising means for rotatably supporting a core about which yarn is to be wound, a drive means for engaging one end of said core for rotating the same, a second drive means for engaging the other end of said core for rotating the same and means for engaging one of said drives for initially rotating said core and means for disconnecting the said one of said drives and operable for connecting the other of said drives to rotate said core, each of said drives rotating said core in the same direction.

3. A strand winding machine comprising means for rotatably supporting a core about which yarn is to be wound, separate independent drives for rotating said core, one of said drives having a plurality of driving fingers slidably mounted for movement to and out of engagement with said core and the other of said drives having interlocking engagement with said core.

4. A strand winding machine comprising means for rotatably supporting a core about which yarn is to be wound, separate independent drives for rotating said core, and a common friction drive means for transferring motion to either of said drives, each of said drives rotating said core in the same direction.

5. A strand winding machine as set forth in claim 4 wherein said common means include a friction drive wheel pivotally supported for movement into and out of engagement with one of said drives.

6. A strand winding machine comprising means for rotatably supporting a core about which yarn is to be wound, separate drives for rotating said core, a friction wheel for one of said drives, a friction drive wheel movably mounted for movement to and from engagement with said friction driven wheel, a lock for holding said friction wheels in driving relation with each other, and means operable by the yarn on said core for disengaging the lock.

7. A strand winding machine comprising means for rotatably supporting a core about which yarn is to be wound, separate drives for rotating said core, a friction driven wheel for one of said drives, a friction drive wheel movably mounted for movement to and from engagement with said friction driven wheel, a lock for holding said friction wheels in driving relation with each other, and means operable by the yarn on said core for disengaging the lock, and resilient means for moving said friction wheels out of engagement with each other.

8. A strand winding machine comprising means for rotatably supporting a core about which yarn is to be wound, separate drives for rotating said core, a friction driven wheel for one of said drives, a friction drive wheel movably mounted for movement to and from engagement with said friction driven wheel, a latch and catch for holding said friction wheels in driving relation with each other, and means operable by the

yarn on said core for disengaging the latch from said catch.

9. A strand winding machine comprising means for rotatably supporting a core about which yarn is to be wound, separate drives for rotating said core, a friction driven wheel for one of said drives, a friction drive wheel movably mounted for movement to and from engagement with said friction driven wheel, a latch and catch for holding said friction wheels in driving relation with each other, and means operable by the yarn on said core for disengaging the latch from said catch, and resilient means for moving said friction wheels out of engagement with each other.

10. A strand winding machine comprising means for rotatably supporting a core about which yarn is to be wound, separate drives for rotating said core, a friction driven wheel for one of said drives, a friction drive wheel movably mounted for movement to and from engagement with said friction driven wheel, cam-operated means for moving said friction drive wheels into frictional engagement with each other, resilient means operable for moving said friction wheels out of driving relation with each other, a lock for holding said friction wheels in driving relation with each other, and means operable by the yarn on said core for disengaging the said lock.

11. A strand winding machine comprising means for rotatably supporting a core about which yarn is to be wound, separate drives for rotating said core, each of said drives including a friction driven wheel, a friction drive wheel movably mounted for movement to and from engagement with either of said friction driven wheels, a cam-operated means for moving said friction drive wheel into engagement with one of said friction driven wheels and resilient means for moving said friction drive wheel out of engagement with the said one of said friction driven wheels and into engagement with the other friction driven wheel.

12. A strand winding machine comprising spaced centers for rotatably supporting a core about which yarn is to be wound, each of said centers being slidably mounted for movement to and from said core, a core engaging driving means adjacent each of said centers for engagement with said core for driving the same, separate means for rotating either one of said core engaging means, and cam-operable means for moving said centers out of engagement with said core.

13. A strand winding machine comprising spaced centers for rotatably supporting a core about which yarn is to be wound, one of said centers being a drive center, means on said drive center for engaging said core for rotating the same, driving means for rotating said drive center, and means including a wheel eccentrically mounted and positioned to be engaged by the yarn on said core upon said core being filled and moved radially from said core to set into motion means for arresting the said driving means.

14. A strand winding machine comprising means for rotatably supporting a core about which yarn is to be wound, a traverse for moving the yarn back and forth across said core, driving means for rotating said core, means automatically operable for doffing, means includ-

ing an eccentrically mounted wheel positioned to be engaged by the yarn on said core to be moved thereby radially of said core upon said core being filled operable to set into motion means for disengaging the yarn from the traverse and arrest the driving means and set into motion the doffing means.

15. A strand winding machine comprising means for rotatably supporting a core about which yarn is to be wound, a traverse for moving the yarn back and forth across said core, separate driving means for rotating said core, means for removing a filled core from said support and means for positioning an empty core adjacent said support to be engaged thereby, and means carried by one of said drive means and rotatable therewith for attaching the yarn strand to the empty core.

16. A strand winding machine comprising support means for rotatably supporting a core at the ends thereof, cam-operated means for moving said support means into and out of engagement with said core, a traverse for moving the yarn back and forth across said core, a first drive means for initially rotating said core from one end thereof, a second drive means separate and independent of said first drive means for rotating said core at the other end thereof and at a greater speed of rotation than driven by the first said means, and cam-operated means operable for disengaging said first drive means and engaging the second drive means with said core.

17. In a bobbin winding machine, a bobbin winding mechanism, a hopper for empty bobbins rockably mounted for movement to and from the bobbin winding mechanism, a bobbin transfer mechanism having a pair of flexible fingers for receiving a wound bobbin, and means for actuating said hopper and transfer mechanism in time relation with each other whereby the flexible fingers are moved to receive a wound bobbin from the winding mechanism and the hopper is moved to the winding mechanism for moving an empty bobbin to be received by the winding mechanism and a stripper means for engaging a wound bobbin to strip the same from said fingers.

EVELYN LYNDALL WHITBY.
